SNOW SCOOP

Norbert J. Zahler, Rte. 2, Box 152,
Rogers, Minn. 55374

Filed Oct. 11, 1968, Ser. No. 13,940

Term of patent 14 years

Int. Cl. D15—99

U.S. Cl. D35—2

FIG. 2

FIG. 4

FIG. 3

FIG. 5

FIG. 6

FIG. 1

FIGURE 1 is a perspective view of a snow scoop incorporating my new inventive design;

FIGURE 2 is a plan view of the same;

FIGURE 3 is a left side elevation view of the same, the right side elevation view being a mirror image of the same;

FIGURE 4 is a front end elevation view of the same;

FIGURE 5 is a rear elevation view of the same; and

FIGURE 6 is a bottom view of the same.

I claim:

The ornamental design for a snow scoop, as shown and described.
